(57) **CLAIM**

The ornamental design for a cosmetic dispenser, as shown and described.

DESCRIPTION

FIG. 1 is a top perspective view of a cosmetic dispenser showing our new design;

FIG. 2 is a front elevation view thereof, the rear elevation view being identical;

FIG. 3 is a top plan view thereof, shown at an enlarged scale;

FIG. 4 is a bottom plan view thereof;

FIG. 5 is a left side elevation view thereof, shown at the scale of FIGS. 1 and 2, the right side elevation view being identical;

FIG. 6 is a top, front, right side perspective view of a second embodiment of our new design;

FIG. 7 is a front elevation view thereof;

FIG. 8 is a rear elevation view thereof;

FIG. 9 is a bottom plan view thereof, shown at an enlarged scale, the top plan view being identical to that of FIG. 3; and,

FIG. 10 is a left side elevation view thereof, shown at the scale of FIGS. 6, 7 and 8, the right side elevation view being a mirror image.

The broken lines form no part of the claimed design. The claimed design extends to the broken line boundary but does not include the boundary.
